UNITED STATES PATENT OFFICE.

ARVID E. ANDERSON, OF SCHENECTADY, NEW YORK, ASSIGNOR TO GENERAL ELECTRIC COMPANY, A CORPORATION OF NEW YORK.

AUTOMATIC RECLOSED CIRCUIT-BREAKER SYSTEM.

Application filed October 3, 1923, Serial No. 688,421. Renewed May 26, 1928.

My invention relates to automatic reclosing circuit breaker systems and is particularly applicable to the type of automatic reclosing circuit breaker system used to connect together two electric circuits both of which, at certain times, are independently energized and only one of which, at other times is independently energized. One object of my invention is to provide an improved automatic reclosing circuit breaker system of this type which will operate to close the circuit breaker, which is arranged to connect the circuits together, when either one or both of the circuits are energized.

My invention will be better understood from the following description taken in connection with the accompanying drawings and its scope will be pointed out in the appended claims.

In the accompanying drawings, Fig. 1 shows diagrammatically one embodiment of my invention for connecting together two circuits which have a common return, Fig. 2 is a modification of the arrangement shown in Fig. 1, Fig. 3 is a modification of the arrangement shown in Fig. 2, Fig. 4 is a modification of the arrangement shown in Fig. 2, the two circuits being provided with independent return circuits, and Figs. 5 and 6 show modifications of the arrangement shown in Fig. 4.

Referring to Fig. 1, 1 and 2 represent respectively conductors of two circuits which are arranged to be connected together by a circuit breaker 3 which may be of any suitable type. The conductors 1 and 2 may for example be considered as the supply conductors of two sections A and B of a trolley circuit of a railway system in which the return circuit of the two sections is through ground. It is apparent, however, that it is immaterial whether a grounded return or a metallic return is used. The sections A and B are assumed to be energized independently from a suitable source or sources not shown, in a manner well known in the art.

Any suitable means may be used for closing the circuit breaker 3 and in the drawing I have shown a closing coil for this purpose. This closing coil 4, when energized, closes the circuit breaker and holds it closed as long as the voltage supplied thereto is above a predetermined value.

It is apparent that if the sections A and B are always supplied with current at nor-

mal voltage, the closing coil 4 of the circuit breaker 3 can always be connected to the same section whenever it is desirable to close the circuit breaker automatically. Since, however, conditions may occur whereby the source which normally supplies current to one section may fail, whereas the other section may be energized, it is apparent that if the closing coil of the circuit breaker is arranged to be connected always to the same section, the circuit breaker can be closed automatically only when the section, to which the closing coil is arranged to be connected, is energized. According to my invention I control the circuit of the closing coil of the circuit breaker so that it is energized from the energized circuit when either one or both of the two circuits, to which it is arranged to be connected automatically, is energized. Therefore in the arrangement shown, in which the sections A and B are the two circuits to which the closing coil is arranged to be connected, it is apparent that as long as either section A or B is energized, the circuit breaker 3 may be reclosed automatically.

In order to energize the closing coil 4 from the section which is energized when only one section is energized, I provide two voltage relays 5 and 6 which control the connections between the closing coil 4 and the sections A and B. The coil of the voltage relay 5 is connected across the section A and is arranged, when energized, to connect the closing coil 4 directly across section A. The coil of the voltage relay 6 is arranged to be connected across the section B when the voltage relay 5 is deenergized. The relay 6, when energized, connects the closing coil 4 across section B. Since the voltage relay 6 is arranged to be energized only when the voltage relay 5 is deenergized, it is apparent that when either section is energized and the circuit breaker 3 is closed, the voltage relay 5 is energized and therefore the circuit for the voltage relay 6 and the circuit of the closing coil 4 controlled thereby are open.

In order that the conductors 1 and 2 may not be connected directly together through the contacts of the voltage relays 5 and 6, either when both of the sections are energized at the same instant when the circuit breaker is open, in which case both of the voltage relays may be simultaneously operated, or when the circuit breaker 3 is closed

due to the energization of section B and the voltage relay 5 connects the closing coil 4 to section A before the voltage relay 6 can open its contacts and disconnect the closing coil 4 from section B, a current limiting device such as a relatively high resistor 7 is connected in the circuit of the closing coil 4 controlled by the voltage relay 5 and another current limiting device such as a relatively high resistor 8 is connected in the circuit of the closing coil 4 controlled by the voltage relay 6. Therefore when both of the voltage relays 5 and 6 are in their energized positions, the resistors 7 and 8 are connected in series between the conductors 1 and 2 so that only a very small current can flow through the contacts of the voltage relays. While I have shown two resistors 7 and 8 it is apparent that the same result may be obtained by omitting either one of the resistors and designing the other resistor so as to limit the current through it under the above mentioned conditions to a predetermined value. I prefer, however, to use two resistors which have substantially the same value of resistance so that the closing coil 4 will have substantially the same voltage impressed thereon when either section is energized.

In order that the circuit breaker may be opened when an excessive current flows from one section to the other, an overload relay 10 is provided which is connected in the circuit between sections A and B when the circuit breaker 3 is closed, and which is arranged to open the circuit of the closing coil 4. The overload relay is arranged in any suitable manner as by means of a dash pot 11, so that it does not close its contacts 13 in the closing coil circuit until a predetermined time after the circuit breaker 3 opens due to the operation of the overload relay 10. When the overload relay closes its contacts, the circuit breaker is reclosed if either one of the sections is energized. In this manner when there is an overload connected to one section and the other section is energized, the circuit breaker is automatically reclosed periodically until the overload is removed or further reclosing is prevented by opening the circuit of the closing coil in any well known manner, not shown.

The operation of the system shown in Fig. 1 is as follows:—Let it be assumed that the circuit breaker 3 is open and only the section A is energized. Voltage relay 5 then becomes energized and, by closing its contacts 12, completes a circuit from the supply conductor 1 of section A through contacts 12 of relay 5, resistor 7, contacts 13 of the overload relay 10, closing coil 4 of the circuit breaker 3 to ground which is the return circuit of section A. The energization of the closing coil 4 closes the circuit breaker 3 which in turn connects section B to section A so that section B is energized. Since the

circuit of the voltage relay 6, which is arranged to be connected across section B, is open at the contacts 15 of the voltage relay 5, the voltage relay 6 is not energized when the circuit breaker closes.

Let it now be assumed that the circuit breaker 3 is open and only the section B is energized. The circuit for the voltage relay 6 is then completed, this circuit being from the supply conductor 2 of section B, through the coil of the voltage relay 6, contacts 15 of the voltage relay 5 to ground which is the return circuit of section B. The closing of the contacts 16 of the voltage relay 6 completes a circuit from the supply conductor 2 of the section B, through contacts 16 of the relay 6, resistor 8, contacts 13 of the overload relay 10, closing coil 4 of the circuit breaker 3 to ground. The energization of the closing coil 4 closes the circuit breaker 3 so that the section 1 is energized. Voltage relay 5 then becomes energized and completes the above traced circuit for the closing coil 4 between the supply conductor 1 of section A and ground. The voltage relay 5 by opening its contacts 15 opens the circuit of the voltage relay 6 which in turn opens the circuit of the closing coil 4 controlled thereby. Since the circuit of the closing coil 4 controlled by the voltage relay 5 is closed before the voltage relay 6 can operate and open the circuit of the closing coil 4 controlled thereby, both circuits of the closing coil 4 are closed for an instant. As mentioned above the resistors 7 and 8 are provided in the circuits of the closing coil 4 so as to prevent an excessive current flowing from one section to the other through the contacts 12 and 16 of the voltage relays 5 and 6 respectively under this condition. As soon as the voltage relay 6 opens its contacts 16 only the closing coil circuit through the contacts 12 of the voltage relay 6 remains completed.

It is apparent that if both sections are energized simultaneously when the circuit breaker 3 is open, both of the circuits of the closing coil 4 are completed for an instant. The opening of the contacts 15 of the relay 5 however, deenergizes relay 6 so that closing coil circuit through the contacts 16 of the relay 6 is opened. After the circuit breaker is closed it remains closed as long as either section is independently energized and the current through the circuit breaker does not exceed a predetermined value. It is obvious that if the voltage across both sections drops below a predetermined value, the voltage relay 5 opens the circuit of the closing coil 4 and the circuit breaker opens and remains open until the voltage on one of the sections increases above a predetermined voltage determined by the setting of the voltage relay connected thereto.

When the circuit breaker 3 is closed and

- the current through the circuit breaker exceeds a predetermined value the overload relay 10 opens its contacts 13 and deenergizes the closing coil 4 of the circuit breaker 3 so that the circuit breaker opens. After a predetermined time determined by the setting of the dash pot 11, the overload relay 10 again closes its contacts 13 and the closing coil 4 is connected across the energized section in the manner heretofore described. If the abnormal condition is still connected to the system when the circuit breaker 3 recloses, the overload relay operates again and the above cycle of operation is repeated until either the abnormal condition is removed or the circuit of the closing coil 4 is opened in any well known manner, not shown.
- In the modification of my invention shown in Fig. 2, the overload relay 10 controls the closing coil 20 of a second circuit breaker 21 which when opened, inserts a current limiting device 22, shown as a resistor, in series between the two sections A and B so as to limit the flow of current from one section to the other when an abnormal condition occurs on one section and the other section is energized. The circuit of the closing coil 20 is arranged to be completed by means of the auxiliary contacts 23 on the circuit breaker 3 which are closed only when the circuit breaker 3 is closed. Therefore the circuit breaker 21 can be closed only after the circuit breaker 3 is closed. The closing coil 20 may be connected across one of the sections such as section A as shown in Fig. 2, since both sections are energized after the closing of the circuit breaker 3 or it may be connected to either section by the relays 5 and 6 in the same way that the closing coil 4 is connected to either section. This result may be obtained, for example, by connecting the coil 20 in parallel with the closing coil 4 of the circuit breaker 3 in the manner shown in Fig. 3.
- The overload relay 10 and the resistor 22 are so designed that when the circuit breaker 21 is open, sufficient current is supplied to the section to which the abnormal condition is connected to maintain the contact 13 of the overload relay open as long as the abnormal condition remains connected to the section. In order to prevent the resistor 22 from overheating when the circuit breaker 21 is open, a thermostat 25 is placed near the resistor so as to be affected by the temperature thereof. This thermostat is arranged to effect the opening of the circuit breaker 3 so as to disconnect the two sections A and B from each other when the temperature of the resistor 22 exceeds a predetermined value and to maintain said circuit breaker open until the temperature of the resistor decreases below a predetermined value. As shown in Fig. 2 this result is obtained by having the thermostat open the contacts 26 in the circuit of the voltage relay 5 and close the contacts 27 in shunt around the coil of the voltage relay 6 when the temperature of the resistor exceeds a predetermined value. As shown in Fig. 3 this result is obtained by having the thermostat open the contacts 26 and 28 in the circuits of the voltage relays 5 and 6 respectively.
- In order to prevent a short circuit being maintained across the section B in Fig. 2 when the contacts 27 of the thermostat are closed, a high resistance 29 is provided in series with the coil of the voltage relay 6 so that it is in series with the contacts 27 when they are closed.
- The operation of the modifications shown in Figs. 2 and 3 so far as the arrangement for connecting the closing coil 4 to an energized section, is the same as in Fig. 1 so that a description thereof is deemed unnecessary. In Fig. 2 when the circuit breakers 3 and 21 are closed and an excessive current flows from one section to the other, the overload relay 10 opens its contacts 13 and the circuit breaker 21 opens. As long as an abnormal condition remains connected to one section and the other section is energized, sufficient current flows through the resistor 22 to maintain the contacts 13 of the overload relay 10 open. If the resistor 22 overheats, the thermostat 25 opens contacts 26 and closes contacts 27 so that the circuit of the voltage relay 5 is opened and the coil of the voltage relay 6 is short circuited. Consequently both of the voltage relays are deenergized and the circuit breaker 4 opens. As soon as the resistor 22 cools and the thermostat 25 opens contacts 27 and closes contacts 26, the circuit breaker 3 is reclosed in a manner heretofore described.
- If there is no overload connected to either section when the circuit breaker 3 closes, the current through the overload relay 10 is not sufficient to operate the relay and therefore the closing of the auxiliary contacts 23 of the circuit breaker 3 connects the closing coil 20 of the circuit breaker 21 across section A. The closing of the circuit breaker 20 again connects section A directly to section 3.
- If when the circuit breaker 3 closes, there is a short circuit or overload connected to either section, the overload relay operates and prevents the circuit breaker from closing until the load conditions are normal.
- The operation of the modification shown in Fig. 3 is the same as Fig. 2 except that the opening of the contacts 26 and 28 of the thermostat opens the circuit of both of the voltage relays 5 and 6 and the closing coil 20 is arranged to be connected in parallel with the closing coil 4 instead of always being connected across section A.
- In the systems shown in Figs. 1, 2 and 3 the sections A and B have a common return

circuit, which may be ground, and the circuit breaker 3 only opens the connection between the supply conductors 1 and 2. Therefore in such systems one terminal of the closing coil 4 can be connected directly to the common circuit and the voltage relays 5 and 6 have to control the connection of only one terminal of the closing coil 4 in order to connect the coil across the respective sections when the circuit breaker is open.

When, however, it is necessary to open the connection between both conductors of the two sections when they are disconnected from each other, the voltage relays have to be arranged to connect both terminals of the closing coil to the conductors of the respective sections. In Fig. 4, which is a modification of the arrangement shown in Fig. 2, the return circuit instead of being the ground, consists of conductor 31 for section A and conductor 32 for section B. The circuit breaker 3, when closed respectively connects conductors 1 and 31 of section A to conductors 2 and 32 of section B.

The closing coil 4 of the circuit breaker 3 is arranged to be connected across section A through the contacts of the voltage relay 5 and is arranged to be connected across section B through the contacts of the voltage relay 6. The contacts 12 of the voltage relay 5 are arranged to connect one terminal of the closing coil 3 to conductor 1 of section A and contacts 16 of the voltage relay 6 are arranged to connect the same terminal of the closing coil 3 to conductor 2 of section B in the same manner as in Fig. 2. The other terminal of the closing coil 4 however, is arranged to be connected to conductor 31 of section A by contacts 33 of relay 5 and to conductor 32 of section B by contacts 34 of relay 6. As mentioned above the resistors 7 and 8 are connected in series between the closing coil 4 and the conductors 1 and 2 respectively so as to limit the current through the contacts 12 and 16 of the relays 5 and 6 respectively in case both of these contacts are closed at the same time. For the same reason the resistors 35 and 36 are connected in series between the closing coil 4 and the conductors 31 and 32 respectively so as to limit the current through contacts 33 and 34 when both of these contacts are closed at the same instant.

The voltage relays 5 and 6 are respectively connected between the conductors of sections A and B in the same manner as shown in Fig. 2 except that instead of being connected directly to the return conductors of the respective sections a current limiting device is connected in series therewith. As shown in Fig. 4 a resistor 38 is connected in series between the conductor 31 of section A and the coil of the voltage relay 5, and a resistor 39 is connected in series between the conductor

32 of section B and the coil of the voltage relay 6. These two resistors are so connected in the respective circuits that when the circuit breaker 3 is open they are connected in series between conductors 31 and 32 and therefore limit the amount of current that can flow from one conductor to the other when the circuit breaker 3 is open. Resistors 29, 38 and 39, and coils of relays 5 and 6 are preferably selected so that both relays operate in response to substantially the same voltages.

Since the operation of the arrangement shown in Fig. 4 is the same as the arrangement shown in Fig. 2, a description thereof is believed to be unnecessary.

The arrangement shown in Fig. 5 is the same as the arrangement shown in Fig. 4 except that the circuit breaker 3 is replaced by two circuit breakers 3^A and 3^B, the resistors 8, 35, 38 and 39 have been omitted and the thermostat 25 connects the voltage relays 5 and 6 across the sections A and B in the manner shown in Fig. 3.

The circuit breaker 3^A is arranged to connect the conductors 1 and 2 together and the circuit breaker 3^B is arranged to connect the conductors 31 and 32 together. The closing coils 4^A and 4^B are connected in series with each other, and the circuit of these coils is completed by the voltage relays 5 and 6 in the same way as shown in Fig. 4. It will be observed that in case the contacts 12 and 16 and the contacts 33 and 34 of the voltage relays 5 and 6 are closed at the same instant the resistor 17 will limit the current flowing between conductors 1 and 2 through contacts 12 and 16 and resistor 36 will limit the current flowing between conductors 31 and 32 through contacts 33 and 34.

By arranging the circuits of the voltage relays 5 and 6 so that separate contacts of the thermostat 25 connect the relays across the respective sections, the resistors 38 and 39 may be omitted since the circuits of these two relays are entirely independent of each other.

In the modification of Fig. 5 shown in Fig. 6, the voltage relay 6 is omitted and the closing coils 4^A and 4^B are arranged to be connected across section B by contacts of the voltage relay 5 when section A is not energized, the closing coils 4^A and 4^B being arranged so that they close when the voltage impressed thereon exceeds a predetermined value. The contacts 16 of the voltage relay 6 in Fig. 5 are replaced by the contacts 40 of the relay 5 which are closed when the relay 5 is deenergized and the contacts 34 of the relay 6 are replaced by the contacts 41 of the relay 5. The contacts 28 of the thermostat are connected in the circuit of the closing coils 4^A and 4^B, which is arranged to be connected across section B.

It will be observed that when the circuit

breakers 3^a, 3^b and 21 are open and section A is not energized a circuit is completed from the conductor 2 of section B through contacts 40 of the voltage relay 5, closing coil 4^b, closing coil 4^a, resistor 36, contacts 41 of the voltage relay 5, contacts 28 of the thermostat 25 to the conductor 32 of section B. Therefore if section B is energized, the circuit breakers 3^a and 3^b close and relay 5 becomes energized so that the above traced circuit is opened at contacts 40 and 41 of the relay 5. The relay 5 is arranged, however, so that it closes its contacts 12 and 33 before it opens its contacts 40 and 41. 15 Therefore a circuit is completed from conductor 1 of section A through contacts 12 of the voltage relay 5, resistor 7, closing coil 4^b, closing coil 4^a, contacts 33 of relay 5 to the conductor 31 of section A to maintain 20 the closing coils 4^a and 4^b energized after the contacts 40 and 41 are opened. During the time the contacts 12 and 40 are simultaneously closed the resistor 7 limits the current flowing between conductors 1 and 2 25 through these contacts and during the time the contacts 33 and 41 are simultaneously closed the resistor 36 limits the current flowing between conductors 31 and 32.

It is believed that the rest of the operation 30 of the arrangement shown in Fig. 6 is obvious from the description heretofore given of the other arrangements.

While I have shown and described several 35 embodiments of my invention, I do not desire to be limited thereto but seek to cover in the appended claims all those embodiments and modifications thereof that fall within the true spirit and scope of my invention.

40 What I claim as new and desire to secure by Letters Patent of the United States, is,—

1. In an automatic reclosing circuit breaker system, two electric circuits adapted to be energized independently of each other, a circuit breaker arranged to connect said circuits together, a closing coil for said circuit breaker, means responsive to a predetermined voltage across one of said electric circuits for completing an energizing circuit 45 for said closing coil across said one of said electric circuits, another energizing circuit for said closing coil arranged to be completed across the other of said electric circuits, and a current limiting device in one of the circuits of said closing coil arranged to be connected in a shunt circuit around said circuit breaker to limit the flow of current between said electric circuits only when both of said energizing circuits are simultaneously completed.

2. In an automatic reclosing circuit breaker system, two electric circuits adapted to be energized independently of each other, a circuit breaker arranged to connect said circuits together, a closing coil for said cir-

cuit breaker, means responsive to a predetermined voltage across one of said electric circuits for completing an energizing circuit for said closing coil across said one of said electric circuits, means responsive to a predetermined voltage across the other of said electric circuits for completing an energizing circuit for said closing coil across said other of said electric circuits, and a current limiting device in one of said energizing circuits arranged to be connected in a shunt circuit around said circuit breaker to limit the flow of current between said electric circuits only when both of said voltage responsive devices are simultaneously energized. 70 75 80 85 90 95 100 105 110 115 120 125 130

3. In an automatic reclosing circuit breaker system, two electric circuits adapted to be energized independently of each other, circuit interrupting means arranged to connect said electric circuits together, electroresponsive means for closing said circuit interrupting means, a current limiting device, means responsive to the voltage across one of said electric circuits for connecting said electroresponsive means and said current limiting device in series across said one of said electric circuits, a second current limiting device, and means responsive to the voltage across the other one of said electric circuits only when said circuit interrupting 135 means is open for connecting said electroresponsive means and said second current limiting device across said last mentioned electric circuit, said current limiting devices being so connected that only when both of said voltage responsive means are simultaneously energized said devices are connected in series with said electric circuits.

4. In an automatic reclosing circuit breaker system, two electric circuits adapted to be energized independently of each other, a circuit breaker arranged to connect said circuits together, a closing coil for said circuit breaker, a circuit for said closing coil arranged to be completed across one of said electric circuits when said one of said electric circuits is energized, a relay responsive to the voltage across said one of said circuits for controlling the circuit of said closing coil, another circuit for said closing coil arranged to be completed across the other one of said electric circuits, and means controlled by said relay for preventing the completion of said last mentioned circuit for said closing coil after said relay has operated to complete the first mentioned circuit for said closing coil.

5. In an automatic reclosing circuit breaker system, two electric circuits adapted to be energized independently of each other, a circuit breaker arranged to connect said circuits together, a closing coil for said circuit breaker, a circuit for said closing coil arranged to be completed across one of said electric circuits, a voltage relay responsive

to the voltage across said one of said electric circuits for controlling the circuit of said closing coil, another circuit for said closing coil arranged to be connected across the other one of said electric circuits, a voltage relay responsive to the voltage across said other one of said electric circuits for controlling said last mentioned circuit for said closing coil, and means controlled by said first mentioned voltage relay for preventing the completion of said last mentioned circuit for said closing coil after said first mentioned voltage relay has operated to complete the first mentioned circuit for said closing coil.

6. In an automatic reclosing circuit breaker system, two electric circuits adapted to be energized independently of each other, a circuit breaker arranged to connect said circuits together, a closing coil for said circuit breaker, a circuit for said closing coil arranged to be completed across one of said electric circuits, contacts in said closing coil circuit, a voltage relay responsive to a predetermined voltage across said one of said electric circuits for closing the contacts in said closing coil circuit, another circuit for said closing coil arranged to be connected across the other one of said electric circuits, contacts in said last mentioned closing coil circuit, a voltage relay responsive to a predetermined voltage across said other one of said circuits for closing said contacts in said last mentioned closing coil circuit, and contacts in the circuit of said last mentioned voltage relay controlled by said first mentioned voltage relay whereby said last mentioned voltage relay can be energized only when said first mentioned voltage relay is deenergized.

7. In an automatic reclosing circuit breaker system, two electric circuits adapted to be energized independently of each other, a circuit breaker arranged to connect said circuits together, a closing coil for said circuit breaker, a circuit for said closing coil arranged to be completed across one of said electric circuits, a resistor in said circuit of said closing coil, contacts in said circuit of said closing coil, a voltage relay responsive to a predetermined voltage across said one of said electric circuits for closing the contacts in the circuit of said closing coil, another circuit for said closing coil arranged to be completed across the other one of said electric circuits, a resistor in said last mentioned closing coil circuit, contacts in said last mentioned closing coil circuit, a voltage relay responsive to a predetermined voltage across said other one of said electric circuits for closing said last mentioned closing coil circuit, and contacts in the circuit of said last mentioned voltage relay controlled by said first mentioned voltage relay whereby said last mentioned voltage relay can be ener-

gized only when said first mentioned voltage relay is deenergized.

8. In an automatic reclosing circuit breaker system, two electric circuits adapted to be energized independently of each other, a current limiting device, an overload relay, a circuit breaker arranged to connect said current limiting device and said overload relay in series between said circuits, a second circuit breaker arranged to short circuit said current limiting means, an operating coil for said second circuit breaker controlled by said overload relay and said first mentioned circuit breaker, an operating coil for said first mentioned circuit breaker, and voltage responsive means for selectively connecting the operating coil for said first mentioned circuit breaker across the electric circuit which is energized when one of said electric circuits is energized.

9. In an automatic reclosing circuit breaker system, two electric circuits adapted to be energized independently of each other, a current limiting resistor, an overload relay, a circuit breaker arranged to connect said resistor and said overload relay in series between said circuits, a second circuit breaker arranged to short circuit said current limiting means, a closing coil for said second circuit breaker, a circuit for said closing coil arranged to be completed when said first mentioned circuit breaker is closed and the current through said overload relay is less than a predetermined value, a closing coil for said first mentioned circuit breaker, a circuit for the closing coil of said first mentioned circuit breaker arranged to be completed across one of said electric circuits, a relay responsive to the voltage across said one of said electric circuits for controlling said circuit of the closing coil of the first mentioned circuit breaker, another circuit for the closing coil of the first mentioned circuit breaker arranged to be completed across the other electric circuit when said relay is deenergized, and means responsive to the temperature of said current limiting resistor for controlling both of the circuits of the closing coil of said first mentioned circuit breaker.

10. In an automatic reclosing circuit breaker system, two electric circuits adapted to be energized independently of each other, a current limiting resistor, an overload relay, a circuit breaker arranged to connect said resistor and said overload relay in series between said circuits, a second circuit breaker arranged to short circuit said current limiting means, a closing coil for said second circuit breaker, a circuit for said closing coil arranged to be completed when said first mentioned circuit breaker is closed and the current through said overload relay is less than a predetermined value, a closing coil for said first mentioned circuit breaker, means re-

- sponsive to the voltage across one of said electric circuits for connecting the closing coil for said first mentioned circuit breaker across said one of said electric circuits when said one of said electric circuits is energized, means responsive to the voltage across the other one of said electric circuits for connecting the closing coil for said first mentioned circuit breaker across said other one of said electric circuits when only said other one of said circuits is energized, and means responsive to the temperature of said current limiting resistor for rendering both of said voltage responsive means inoperative to close the circuit of the closing coil of said first mentioned circuit breaker when the temperature of said resistor exceeds a predetermined value.
11. In an automatic reclosing circuit breaker system in which two sections of an electric system are connected together by means of a circuit breaker, a coil for controlling the closing of the circuit breaker, a circuit for said coil connected across one of said sections, another circuit for said coil connected across the other of said sections, contacts connected so that the closing thereof completes only one of said circuits, a relay responsive to the voltage across one of said sections for effecting the closing of said contacts when the voltage impressed on said relay exceeds a predetermined value, current limiting means in one of said coil circuits connected so as to be in series between said sections when both of said circuits are completed at the same time, and switching means arranged to be operated to effect the opening of the circuit controlled by said relay when the other circuit is completed.
12. In an automatic reclosing circuit breaker system in which two sections of an electric system are connected together by means of a circuit breaker, a coil for controlling the closing of the circuit breaker, a circuit for said coil connected across one of said sections, another circuit for said coil connected across the other one of said sections, contacts connected so that the closing thereof completes only one of said coil circuits, a relay responsive to the voltage across one of said sections for effecting the closing of said contacts, current limiting means in one of said circuits connected so as to be in series between said sections when both of said circuits are completed at the same time, and means controlled by said relay for preventing the completion of the other coil circuit after said relay has effected the completion of said one of said coil circuits.
13. In an automatic reclosing circuit breaker system in which two sections of an electric system are connected together by means of a circuit breaker, a coil for controlling the closing of the circuit breaker, two circuits for said coil, a relay responsive to the voltage of one of said sections for completing one of said circuits across said one of said sections to effect the energization of said coil from said one of said sections when the voltage across said one of said sections is above a predetermined value, a second relay responsive to the voltage across the other section for completing the other circuit across said other section to effect the energization of said coil from said other section when the voltage across said other section is above a predetermined value, and current limiting means in one of said circuits arranged so as to be connected in series between said sections only when both of said circuits are simultaneously completed.
14. In an automatic reclosing circuit breaker system in which two sections of an electric system are connected together by means of a circuit breaker, a coil for controlling the closing of the circuit breaker, two circuits for said coil, one of said circuits being across one of said sections so that said one of said circuits is energized by the voltage across said one of said sections, a relay responsive to the voltage across the other section for connecting the other circuit of said coil across said other section to effect the energization of said coil from said other section when the voltage across said other section is above a predetermined value, and current limiting means in one of said coil circuits arranged so as to be connected in series between said sections only when both of said circuits are simultaneously completed.

In witness whereof, I have hereunto set my hand this 2nd day of October, 1923.

ARVID E. ANDERSON.
